UNITED STATES PATENT OFFICE.

HUGO REIMANN, OF RACINE, WISCONSIN.

CURTAIN-ROLLER BRACKET.

SPECIFICATION forming part of Letters Patent No. 721,833, dated March 3, 1903.

Application filed February 26, 1902. Serial No. 95,714. (No model.)

To all whom it may concern:

Be it known that I, HUGO REIMANN, a citizen of the United States, residing at Racine, in the county of Racine and State of Wisconsin, have invented certain new and useful Improvements in Curtain-Roller Brackets; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to curtain-roller brackets, and has for its object the production of a support for the ends or spindles of the ordinary spring-roller curtain-pole which may be attached in position without separate screws 20 or nails and that is in itself small and hardly noticeable when in position.

Each constituent element of my invention is described in detail and its individual office, together with the mode of operation of the 25 whole, fully explained hereinbelow.

I accomplish the objects stated by employing the construction illustrated in the accompanying drawings, in which—

Figure 1 represents a curtain-roller of customary pattern supported by my invention, a portion of a window-frame being also shown, with certain parts in section to exhibit the arrangement of the details in the preferred form. Fig. 2 illustrates the side view of my invention. This view may be taken for either of 35 the pair of brackets of the couple employed for each curtain-roller. Figs. 3 and 4 represent front views of the pair of brackets, showing the difference in the shape of the orifice 40 with which each is provided.

Considering the drawings, letter A marks the bracket, having the rectangular orifice α , provided with the shoulder α' . This orifice is intended to receive the flattened extremity of the spring-spindle B of the curtain-roller C. The office of the rectangular orifice α is to prevent the rotation of the spring rod or spindle B, causing the spring in the roller to be wound up as the curtain is drawn down- 45 wardly and to raise the curtain by unwind-

ing in the ordinary manner. A front view of bracket A is given in Fig. 3.

Letter D designates the bracket having the circular orifice d to receive the cylindrical or rotatory spindle E, which spindle turns with 55 the roller. Fig. 4 shows the front of the bracket D.

The general form of the brackets is substantially the same. A description of bracket D will therefore apply equally to the bracket 60 A. In the side view, Fig. 2, it will be seen that the body portions of the brackets are hemispherical, and in Fig. 1 it is shown that these hemispherical body portions are hollow. Upon each side of the orifice d of the bracket 65 D there projects a spike, formed integrally with the body of the bracket, upon the rear edge thereof. In Fig. 2 the spikes for the bracket D are marked d' and d'' . I do not limit myself to two spikes for each bracket, 70 as a third or fourth might be added within the purview of my invention.

The brackets may be fashioned of any suitable metal, usually malleable iron, and the brackets are secured in position upon a window-frame F by driving the spikes more or less into the wooden pieces of the frame, properly situated to receive them. If necessary, small holes may be made in the wood 75 with an awl to start the spikes, and, as stated, 80 they are driven more or less into the wood, according as the curtain-roller is less than or exceeds the space across the window where the brackets are placed. The hollow hemispherical body portion of my invention is 85 practically the head of the spike or spikes, which are to be driven into the window-frame by blows on the hemisphere or cup, and the particular reason for forming the body portion in the shape shown and described is that 90 the hollow hemisphere is easily made and has been determined by trial to be the construction most successful in withstanding the driving blows. The cupped body more effectively resists fracture and distortion under per- 95 cussion than any other form.

I am aware that curtain-roller brackets have been constructed possessing spikes to be driven into the supporting window-frame, and I do not claim that feature broadly. 100

What I claim, and desire to secure by Letters Patent of the United States, is—

A curtain-roller bracket consisting of a single piece of metal formed into a hollow, hemispherical body portion having an orifice 5 adapted to receive the spindle of a curtain-roller, and the said hollow, hemispherical body portion being provided at diametrical points of its edge with spikes integral with 10 the said body, the said hollow body acting as

the head of the spikes to receive the blows driving the spikes and to resist distortion, substantially as described.

In testimony whereof I affix my signature in presence of two witnesses.

HUGO REIMANN.
